(57) CLAIM

The ornamental design for an easy wear medical apparel set, as shown and described.

DESCRIPTION

FIG. 1 is a front perspective view of a shirt of the easy wear medical apparel set, the pants component removed for clarity;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a front perspective view of a pair of pants of the easy wear medical apparel set, the shirt component removed for clarity;

FIG. 9 is a front view thereof;

FIG. 10 is a rear view thereof;

FIG. 11 is a left side view thereof;

FIG. 12 is a right side view thereof;

FIG. 13 is a top view thereof; and,

FIG. 14 is a bottom view thereof.

The broken lines shown in the views are included for the purpose of illustrating portions of the easy wear medical apparel set that form no part of the claimed design.

1 Claim, 9 Drawing Sheets
